[57] **ABSTRACT**

A gas turbine has a fluidic control system having a fluidic bistable element which controls a switch actuator. The vent of the bistable element is fed to a venturi tube. The throat of the venturi tube is connected to one control inlet of the bistable element, the venturi being vented to a pressure equal to or less than the pressure applied to the inlet of the bistable element.

The control system is operative to trigger the actuator which in turn controls the gas turbine when the ratio of main inlet pressure of the bistable element to the pressure at the second control inlet falls below a predetermined value; the pressures being respectively taken from the high pressure compression stage and the fan stage of the gas turbine compressor.

FLUIDIC CONTROL SYSTEMS

The present invention relates to fluidic control systems.

The present invention provides a fluidic control system comprising a fluidic actuator, a fluidic element having an inlet for receiving a first fluid pressure and two control inlets for respectively receiving second and third fluid pressures, said fluidic element being responsive to the pressure difference at the two control inlets to control the fluidic actuator in dependence thereon, and a venturi tube supplying said second fluid pressure from its throat, said venturi tube being connected to receive fluid having a pressure which is substantially proportional to said first fluid pressure whereby to cause the fluidic actuator to operate when the ratio of the first to the third fluid pressures reaches a predetermined value.

According to the invention, there is also provided a gas turbine including an inlet fan stage and a high pressure compressor stage, a bistable fluidic element having a supply inlet and first and second control inlets and two output legs and an exhaust vent, the supply inlet being connected to receive pressure from said high pressure compressor stage and the first control inlet being arranged to receive pressure from said fan stage, a venturi tube connected to receive pressure from said exhaust vent and having a throat which communicates pressure to said second control inlet, and an actuator, said actuator being responsive to the pressure differential supplied from said output legs to modify the operation of said gas turbine whenever the ratio of the pressures at said fan stage and the compressor stage reaches a predetermined value.

A fluidic control system embodying the invention will now be described by way of example with reference to the accompanying diagrammatic drawings in which:

FIG. 1 is a circuit diagram of the fluidic control system;

FIG. 2 is a circuit diagram of a modified form of the fluidic control system;

FIG. 3 is a circuit diagram of a further modified form of the fluidic control system; and

FIG. 4 is a graph showing the input pressure ratio as a function of both control pressure ratio and output pressure ratio of the fluidic control system of FIG. 1.

The fluidic control system of FIG. 1 is primarily intended to monitor the ratio of the pressure P_4 in the high pressure stage 7, and the pressure PF in the fan stage 9, inside the compressor of a gas turbine engine 11.

As shown in FIG. 1, a bistable fluidic element 6 has an input 8 which is connected to receive the pressure P_4 through a pressure ratio setting adjuster 10. The adjuster 10 causes a drop in the pressure P_4 so that the actual pressure at the input 8 is P_s . The element 6 has two control jet inputs 12 and 14, one of which (12) is connected to receive the pressure PF .

The vent 16 of the bistable element is fed into a venturi tube 18, and the throat of the venturi tube 18 is connected to the other control jet input 14. The venturi is vented to a pressure equal to or less than PF .

The bistable element 6 also has two output legs 20 and 22 which are connected to drive the piston 25 of an actuator 24. Thus, when fluid is directed down the leg 20, the actuator piston 25 is urged to the left (as viewed

in FIG. 1) by a pressure PO_2 , and, when fluid is directed down the leg 22, the actuator piston 25 is urged to the right by a pressure PO_1 . The actuator 24 is arranged to operate a microswitch 26.

5 The adjuster 10 comprises a base plate having an inlet and an outlet hole, an adjustable plate having a plurality of pairs of orifices of different sizes, and a clamp plate. All the pairs of holes in the adjustable plate are linked by an annulus formed in the clamp plate so that, by rotating the adjustable plate, a different pair of holes can be placed in communication with the inlet and outlet of the base plate and the pressure drop across the adjuster altered accordingly.

15 In operation, fluid at the pressure P_4 is applied to the pressure ratio setting adjuster 10 which is adjusted to provide the required value of pressure P_s at the input 8 of the fluidic element 6. If the pressure ratio P_4/PO is relatively low, the vent pressure PV will also be relatively low.

20 As the venturi 18 is vented to a pressure equal to or less than PF , the pressure PR at the throat of the venturi 18 will, by virtue of the suction effect produced at the throat, be less than the pressure PF . Hence fluid from the source of pressure P_4 will be directed down the leg 20 and thereby cause the actuator 24 to hold the switch 26 in an OFF condition. If the pressure P_4 then increases relative to the pressure PF , the throat pressure PR will decrease still further until the fluid passing through the throat reaches the speed of sound and the venturi becomes choked. Thereafter a further increase in the pressure P_4 will cause the throat pressure PR to rise until it eventually exceeds the pressure PF . At this moment, the fluid passing down the leg 20 is redirected down the leg 22 which then causes the actuator to operate the switch 26.

25 In this way the switch 26 is operated to indicate that a predetermined value of the ratio P_4/PO has been reached.

30 If the pressure P_4 then drops so that the pressure PR is below the pressure PF the fluid flow through the bistable element 6 will be redirected down the leg 20. However the value of P_4/PO at which this occurs will be slightly lower than the value of P_4/PO at which the original switching occurred because of a hysteresis lag. The electric switch 26 is arranged to control the fuel system of the gas turbine and thereby maintains the pressure ratio P_4/PO either below or above the predetermined value as required.

35 40 Instead the electric switch can be used to control an air valve 13 or other moving part in the gas turbine.

45 FIG. 4 shows a graph of the characteristics of the fluidic control system. Curve A shows the ratio of the differential control pressure $PR-PO$ to the control pressure PO versus the pressure ratio P_4/PO . Curve B shows the ratio of differential output pressure PO_1-PO_2 versus the control pressure PO . The curves show the initial decrease in pressure due to the suction in the venturi throat, the subsequent increase in pressure as the venturi chokes followed by the switching of the bistable element, and clearly indicates the hysteresis effect.

50 55 FIG. 2 shows a modified form of the fluidic control system in which parts similar to those in FIG. 1 are similarly referenced. In this Figure, the venturi tube 18 is not supplied from the vent 16 but instead is supplied direct from the source of pressure P_4 via a pressure ratio setting adjuster 30.

With this system more fluid pressure is available for operating the actuator (not shown) as the adjuster 10 is no longer in the supply path between the source of pressure P_4 and the fluidic element.

However it will be seen that because of this the total fluid consumption of the system is increased.

FIG. 3 shows a system in which a fluidic control system is provided to give an output proportional to the deviation of the pressure ratio P_4/PF from a predetermined value. Here a proportional amplifier 32 is used instead of a bistable element. As in the case of FIG. 2, one control jet input 38 is supplied with pressure P_4 through a variable orifice 36 and a venturi tube 34 while the other control jet input 40 is supplied with the pressure PF . Two output legs 42 and 44 of the proportional amplifier control a ram 46 in dependence upon the pressure difference between the two input control jets. The exhaust vent of the proportional amplifier 32 is provided with a vent restrictor 48 to increase the efficiency of the amplifiers 32.

The ram 46 is coupled to the variable orifice 36 so that if the inlet pressure ratio P_4/PF increases above a datum value in operation, the ram is caused to be displaced in such a sense as to vary the inlet restrictor to reduce the ratio P_4/PF towards its datum value. The ram is then halted when the datum value of P_4/PF is reached.

It will be appreciated that the fluidic system can be used to control a machine or arrangement other than a gas turbine.

I claim:

1. A fluidic control system comprising a fluidic actuator having first and second inlets, a fluidic element having an inlet for receiving a first fluid pressure, two control inlets for respectively receiving second and third fluid pressures and first and second outlets which are respectively connected to the first and second inlets of the fluid actuator, said first pressure inlet, control inlets and first and second outlets being connected to interaction chamber means for producing outlet

pressures at said first and second outlets responsive to the pressure difference at the two control inlets to control the fluidic actuator in dependence thereon,

a venturi tube having an inlet and throat, first means connecting the inlet of the venturi tube to receive a fluid pressure derived from and proportional to said first fluid pressure, and second means connecting the throat to one of said two control inlets of the fluidic element to communicate the second fluid pressure to the said one inlet and means for communicating the third fluid pressure to the other control inlet in an opposing sense whereby to cause the fluidic actuator to operate when the ratio of the first to the third fluid pressures reaches a predetermined value.

2. A system according to claim 1 wherein said fluidic element has an exhaust vent and in which the first means directly couples the exhaust vent to the venturi tube inlet.

3. A system according to claim 1 wherein the first means comprises a variable orifice through which the first fluid pressure is communicated to said venturi tube inlet.

4. A system according to claim 1 wherein the fluidic element comprises a bistable fluidic element which controls the operation of the actuator in an ON/OFF mode.

5. A system according to claim 1 wherein the fluidic element comprises a proportional fluidic amplifier which controls the operation of the actuator in proportion to the difference between said second and third pressures.

6. A system according to claim 5 including a variable fluid restrictor connected to the inlet of said fluidic element and means connecting the actuator to the variable fluid restrictor to vary the magnitude of the first pressure applied to the inlet of the fluidic element in a sense to maintain the ratio of said first to said third pressure constant.
